UNITED STATES PATENT OFFICE.

JOHN F. OHMER AND FREDERICK L. OHMER, OF DAYTON, OHIO.

AUTOMOBILE-SERVICE RECORDER.

1,262,836.

Specification of Letters Patent. Patented Apr. 16, 1918.

Application filed May 21, 1917. Serial No. 169,884.

To all whom it may concern:

Be it known that we, JOHN F. OHMER and FREDERICK L. OHMER, citizens of the United States, residing at Dayton, in the county of 5 Montgomery and State of Ohio, have invented certain new and useful Improvements in Automobile-Service Recorders; and we do declare the following to be a full, clear, and exact description of the invention, 10 such as will enable others skilled in the art to which it appertains to make and use the same, reference being had to the accompanying drawings, and to the letters and figures of reference marked thereon, which form a 15 part of this specification.

This invention relates to means for enabling the owners of automobiles to keep informed as to the extent their machines are being used by others when the owners are 20 not present when the cars are being run. It is well known to the owners of automobiles who employ chauffeurs or those who keep their machines in public garages, that the machines are used by persons without license 25 or permit. The result is that much gasoline is consumed at the expense of the owner and the machines are subjected to wear and tear. The object of the present invention is to provide efficient means whereby the owners 30 of automobiles may detect these unauthorized uses and may identify the person so appropriating the machines without authority.

To the foregoing ends the invention comprises the means hereinafter described and 35 claimed in connection with the accompanying drawings. Referring to these drawings in general terms, Figure 1 is a side elevation of an automobile upon which our improved service control means are mounted. Fig. 2. 40 is a front elevation of the machine with the front portion of the casing removed to disclose the mechanism thereof. Fig. 3 is a sectional view on the line 3-3 of Fig. 2. Fig. 4 is a sectional view approximately on 45 the line 4-4 of Fig. 2. Fig. 5 is a sectional view approximately on the line 5-5 of Figs. 3 and 4. Fig. 6 is a sectional view approximately on the line 6-6 of Figs. 3 and 4. Fig. 7 is a detail view of the actuating devices for the counters which print the mileage 50 on the records taken from the machine. Fig. 8 is a detail view of the actuating means for the counters which print the serial numbers on the records taken from the machine. Fig. 9 is an illustration of a portion of the record sheet taken from the va-

rious printing devices located in the machine and Fig. 10 is a modification of the connections between the fluid control valve and the printing actuating devices of the 60 machine.

Throughout the description to follow and the drawings, similar reference characters are employed to indicate corresponding parts.

65 Mounted upon the rear plate 1 of the machine casing is a frame consisting of a series of parallel walls 2 which support counter shafts 3 and 4 which are shown in dotted lines in Fig. 2. Mounted upon the shaft 3 70 is a trip mileage indicating counter 5 and a season mileage indicating counter 6, and upon shaft 4 are mounted a companion trip mileage printing counter 7 and a season or grand total mileage printing counter 8. The 75 trip counters 5 and 7 register the mileage by tenths and all of the aforesaid counters 5, 6, 7 and 8 may be of any of the well-known types and these counters in the present instance are provided with a well-known 80 form of 1-tooth transfer gears 9, 10 and 11. Other printing or recording counters hereinafter referred to are also mounted on the counter shaft 4. The transfer gears 10 are 85 the driving gears for the counters and are common to both the printing and the indicating or visual counters, and these transfer gears are mounted upon a shaft 12 (Fig. 7). The shaft 12 is the driving shaft for the 90 counters and the same is provided with a worm gear 13 which engages a worm 14 on a shaft 15 journaled in a bearing 16 and the frame 2. The shaft 15 is provided with a worm gear 17 which engages a worm gear 18 on a shaft 19, the latter shaft being journaled in the frame 2 and in a frame 20 attached to the rear plate 1. The said shaft 19 is provided with a beveled gear 21 (Fig. 4), which engages a beveled gear 22 on a 95 shaft 23. The shaft 23 is journaled in a bracket 24 and at its lower end in a bearing or plate 25 attached to the rear plate 1 (Fig. 2). The lower end of plate 23 is connected in a well-known manner to one of the wheels of the vehicle by a flexible shaft 121 (Fig. 105 1). Through the agency of the above train of mechanism the indicating and printing mileage counters referred to are driven from a rotating part of the vehicle, and as is well known, the rotation of these counters 110 corresponds with the distance the vehicle drives. The counters 5 and 7, which as be-

fore stated, indicate and print or record the trip mileage, may be set to zero by any well-known means such as the finger piece 27 (Fig. 2). The shaft 19, in addition to driving the mileage counters, also drives a speedometer which may be of any well known construction. As is illustrated, the shaft 19 is provided with a beveled gear 28 (Fig. 3) which engages a similar gear 29 on a shaft 10 30 which is journaled in a bracket 31 supported by the rear plate 1 and a cross member 32 supported by the frames 2 and 20. The shaft 30 also supports a beveled gear 33 which engages a similar gear 34 mounted 15 upon a vertical shaft 35 journaled in a boss 36 on the bracket 31. The shaft 35 carries a rotating magnet 37 which is shown in Figs. 3 and 4 projecting below an inverted cup 38 in which it revolves, said cup 38 being supported on a shaft 39. The shaft 39 forms a pivot having a bearing in a plate 40 and on the upper end of the shaft 35. The said cup 38 is provided with surface indications or numerical characters which indicate the 20 speed at which the vehicle is driving and the said indicator is controlled in its normal position and is moved to such a position by a suitable spring 41. The rotation of the magnet 37 against the tension of the spring 25 41 rotates the indicator or cup 38 to indicate the speed at which the vehicle drives, in a well-known manner. Mounted upon the counter shaft 4 in proximity to the counter 30 8 which prints the grand total mileage, are two printing wheels 42 and 43 (Figs. 2 and 6) which are instrumental in printing the 35 dates upon the records as shown in Fig. 9. These printing wheels 42 and 43 are provided with gears 44 which engage gears 45 mounted on telescopic shafts 46 and 47. These shafts 46 and 47 are journaled in the frame 2 and on their left-hand sides, as seen in Fig. 6, they are provided with finger 40 pieces 48 which are in turn provided with 45 hands or pointers 49, the latter coöperating with a dial 50 which is on the right-hand side of the casing as shown in Fig. 6. This dial 50 may be provided with the proper indicators to show the months and the days 50 thereof, and the said dial is utilized to determine the movements to be given the date printing wheels 42 and 43 in setting them to the proper position to print the dates as shown on the record (Fig. 9). Also mounted 55 on the counter shaft 4 in proximity to the date printing wheels 42 and 43 is a printing counter 51 (Fig. 6) of any well-known type for printing the serial number on said record. In the present instance, this counter 51 60 is of the 1-tooth transfer type and is provided with transfer gears 52 and 53, the latter being the actuating gears which are mounted on a shaft 54 journaled in the frames 2 and 20. The counter 51 for printing the serial number upon the record is ac-

tuated from the printing mechanism to be hereinafter described. Extending a suitable distance from the frame 2 to the right of the serial numbering counter 51 is a stationary type member 55 which prints on the records 70 taken from the machine from time to time the number of the machine, and near this stationary type member 55 is a key housing 56 supported by the frame 20. The key housing 56 receives a key 57 which is shown 75 in Fig. 2 to be inserted therein. The said key 57 is provided with a suitable type of printing character from which impressions are taken upon the record identifying on the record the operator or person in whose pos. 80 session the key is placed. In the present instance this identification mark on the record (Fig. 9) appears to be "B17". This identification or printing key also performs the function of a locking key to unlock the 85 printing mechanism and for controlling the power for driving the automobile, as will hereinafter appear. The printing counters 7, 8, and 51, the type wheels 42 and 43, the type member 55, and the identification 90 printing key 57 are all arranged in printing alinement and impressions or records such as are shown in Fig. 9 are taken therefrom. Referring to this record in detail, the lowermost impression shows the trip mileage 95 counters to be at zero, for example, when the automobile is taken possession of by a person having a key 57. This key is inserted and the printing mechanism is unlocked thereby. The printing mechanism is then 100 operated by turning the finger piece 70 (Fig. 2) which operation places the automobile in a condition for use, as will hereinafter be apparent. The first impression "0000" discloses the position of the trip mileage count- 105 ers; "0133" an impression from the season or grand total mileage counters; "Aug. 19" the date the first impression was made; "1351" the impression from the serial number printing device; "17" the impression 110 from the machine number printing device; "C3" the number of the key which identifies the holder of that key. After the trip is completed, another or second impression must be made before the key can be withdrawn and the automobile locked out of service. On the record, the second impression "0023" from the trip counters shows that the car was driven two and three-tenths miles; "0185" being the impression from 115 the grand total printing counter; "Aug. 19" showing that the trip was finished on the same day, and the impressions from the serial numbering printer, the machine number printer and the identification key being 120 the same as the first impression. It will be seen that the operation of printing a record at the beginning and ending of each trip is necessary before the car can be placed in a condition for use. The first operation un- 125 130

locks the car, and the subsequent operation locks it until another record is taken. The records are taken by the following means: Extending from the inner face of the plate 1 are two alined lugs 59 to which are pivoted two side plates 61 which support the printing mechanism, the said side plates 61 being supported at their forward or front ends by hook members 62 which are attached to the shaft 4 and engage lugs 63 extending from said plates. This means provides for the lowering and raising of the printing mechanism to allow the insertion of the roll of paper 64 and for the insertion of the strip 65 therefrom between the rollers as shown in Fig. 3. Mounted below the type members hereinbefore described is a platen 66 which is supported on arms 67 pivoted at 68^a to the side plates 61. This platen 66 is arranged to press the paper strip 65 against the printing members to secure the impressions as shown in Fig. 9. In this operation it is elevated by eccentric portions 68 of a shaft 69 the ends of which are journaled in the side plates 61. The said shaft 69 is rotated by the finger piece 70 secured upon a shaft 71 (Fig. 2). The shaft 71 is connected to the right-hand end of the shaft 69 and may be disconnected therefrom when it is desired to lower the printing mechanism with the side plates 61. In addition to operating the platen the shaft 69 is provided with two disks 72 one at each end thereof and upon which are pins 73 which engage the lower ends of levers 74 which support the inking roller 77 (Figs. 3 and 4). The levers 74 are pivoted at 75 and are controlled by springs 76 attached to the ends thereof and to the frame walls 2. During the initial movement of the shaft 69, the inking roller 77 is carried under the type or printing devices to ink the same. The pins 73 release the lever 74 and permit the inking roller 77 to be moved out of the path of the platen 66, before the eccentric portions 68 elevate said platen. After an impression has been made on the record strip 65, the said strip is fed forward between feed rollers 78 which are mounted on shafts 79 journaled in the side plate 61. The roller shaft 79 is the actuating shaft of the pair and on its right-hand end is a Swiss gear 80 which is adapted to be partially moved at each operation of the shaft 69 by a tooth 81 on one of the disks 72 (Fig. 8). This operation takes place at the end of the movement of the shaft 69. The shaft 54 of the consecutive numbering counter 51 is actuated from the printing mechanism by the following means: Attached to the inner side of the right-hand disk 72 is a 1-tooth gear 109 which intermittently engages with a Swiss gear 110 pivoted to the frame 20. Attached to the side of the Swiss gear 110 is a pinion 111 which engages with the gear 112 on the shaft 54. Near the end of the operation of

the shaft 69 the tooth of the gear 109 will partially rotate the shaft 54 and actuate the counter 51. It will be noted that two serial numbers will appear on the record for each service of an operator, that is to say, at the beginning and the end of each trip as shown in the two top and two lower impressions on the record sheet (Fig. 9) where it is shown that "C3" took the car out and returned it in one instance, the serial numbers being "1351" and "1352." And, in the other instance "B17" took the car out and returned it, under serial numbers "1359" and "1360." It will be understood that the first number will be the controlling number for any one particular service or operator. The operation of the printing mechanism and the rotation of the shaft 69 are controlled by the identification key 57. When the said key is removed from its housing 56, the printing mechanism is locked, and upon the insertion of said key it is unlocked. The said key 57 is provided with a pin 82 as shown in Fig. 2 which is adapted to engage a dog 83 pivoted to the key housing and under the influence of a spring 85 which is also attached at one end to the said housing. The said dog is adapted to engage a shoulder 86 on one of the disks 72, the one nearest the key housing. When the dog so engages said shoulder the rotation of the impression shaft 69 is prevented and the printing mechanism is locked. When the key 57 is inserted, the dog 83 is shifted to bring the lower end thereof out of the path of the shoulder 86, and when the said key is removed, the spring 85 will return the disk into the path of the shoulder 86 thereby locking the printing mechanism. The impression shaft 69 is held in its normal position by a spring-controlled pawl 87 mounted in a housing 88 and adapted to enter a suitable recess in the shaft as shown in dotted lines in Fig. 4, in a well-known manner. When the said key is inserted, it cannot be removed unless two impressions are taken from the printing mechanism, the first impression being taken, as before indicated, when a person takes charge of the automobile, and the second impression being taken at the end of that particular service or trip. This is accomplished by the following means:

The impression device 69 is provided with a pinion 89 in engagement with a gear 90, the ratio of the pinion to the gear being one to two. The gear 90 is supported by a bracket 91 attached to one of the side plates 61 and supports the printing devices (Fig. 4). The gear 90 is provided with a projection 92 which is adapted to engage a projection 93 on a pawl 94 which is pivoted to a lug 95 extending from the rear plate 1. The projection 92 holds the pawl 94 in an elevated position when the machine is in a normal condition, the key 57 being removed and

the automobile out of use. When the key is inserted and the printing mechanism has been given its initial operation by turning the finger piece 70, the gear 90, owing as before stated, to its actuating pinion 89 being one-half the diameter thereof, is given a half revolution and the projection 92 releases the projection 93 and thereby permits the pawl 94 to fall in front of a pin 96 extending from the key 57 which, as we have seen, has been previously inserted in its housing. The pawl 94, lying in the path of the pin 96, serves to prevent the key being withdrawn until the projection 92 again elevates the pawl 94, which it does upon the second operation of the printing mechanism. The pawl 94 is braced against any movement of the pin 96 when it is attempted to erroneously remove the key, by a bracket 97 which 20 extends from the key housing 56 (Fig. 6).

Coming now to the features coöperating with the foregoing mechanism or with the printing elements thereof, we will now describe the means through which the motive fluid to the engine (not shown) is controlled. This comprises a suitable valve which is actuated to its open or closed position through the operation of the printing mechanism in taking the records from the machine. The 25 valve 116 is inclosed in a casing 126 fixed to the rear wall 1 of the machine casing. This valve may admit an expansive fluid such as steam or an explosive fluid such as gasoline. Any fluid capable of furnishing power for 30 the engine may be utilized. In the present instance we will refer to the valve as being adapted to admit explosive fluid to that form of an engine, which is not shown. The valve 116 is connected with inlet and outlet 35 pipes 117 and the valve is operated to open and close the passage by the following means:

We have hereinbefore referred to the gear 90 in connection with the printing mechanism, said gear being operated from the pinion 89 when the impression shaft 69 is operated to take an impression from the printing wheels. A cam 99 moves in unison with the gear 90. A roller 101 engages the 40 periphery of the cam 99 and is held in such position by a spring 100. The roller 101 is mounted on the end of a plunger 98 which in turn is mounted in the rear wall 1 of the machine casing. The spring 100 is fixed 45 at one end to the said wall and arranged to engage the end of the plunger 98 on both sides thereof. When the cam 99 rotates it drives the plunger 98 outwardly against the tension of the spring 100 as the highest point 50 of the cam engages the roller. The plunger 98 is connected at its outer end to a valve-operating lever 114 through means of a pin 119 which lies within a slot in an end of said lever. The said lever 114 is pivoted on 55 a fulcrum pin 118 which is mounted in a

bracket extending from the rear wall 1 of the casing. The lever 114 is connected with the movable part of the valve by means of a crank and pin 113, the pin entering a slot in the end of the lever. The cam 99 (Fig. 4) 70 is in the position at which the valve is closed to the admission of the motive fluid to the engine and the automobile is out of service. When the chauffeur or other person desires to use the machine the key 57 is inserted 75 and the printing mechanism is unlocked thereby and in order to admit the motive fluid to the engine the valve 116 must be moved to its open position. This necessitates an impression being taken from the 80 printing devices and in taking this impression the cam 99 is moved to the position opposite that shown in Fig. 4 and the valve is thereby opened through the action of the cam upon the plunger 98. The device remains in this position as long as the machine is in use and the key cannot be withdrawn during this period. After the chauffeur or person using the machine returns to the garage the key is given a second operation 90 in taking the second record and the cam 99 is moved from its former position to the position shown in Fig. 4 thus closing the valve and permitting the removal of the particular key which has been used. The record 95 thus taken at the beginning and ending of the period of service indicates the distance driven and the key used as well as the other data shown on the record sheet in Fig. 3. In Fig. 10 a modification of the valve connection is shown. The valve 116 is shown in this view connected in the pipe 117 directly and the arm 115 of the valve is connected to the plunger 98 by an extended rod or connection 123. In Fig. 10 the valve is 100 shown connecting the pipe 117 between the source of supply and the carburetor 120, the latter being shown in dotted lines in Fig. 1. The inclosing case 102 of the mechanism is conveniently mounted upon the instrument 110 board 122 in front of the driver.

While we have with some particularity described the various mechanism we do not wish to unnecessarily limit ourselves to details, as it will be apparent to those skilled 115 in the art that various modifications may be made without departing from the underlying principles of our invention which involve a control of the motive fluid to the engine through the operation of impression or 120 printing mechanism which is instrumental in taking records from the various instrumentalities which show the service of the automobile upon which the devices are used.

Having described our invention we claim: 125

1. In a machine of the character specified, the combination with mileage recording counters, impression devices coöperating therewith in taking a record from said counters of the mileage a car has traveled 130

for any given period, and means controlling the operative relation between said counters and impression devices, of a valve controlling the discharge of motive fluid to the engine which furnishes the propelling power for said car, and means actuated by said impression devices for operating said valve.

2. In a machine of the character specified, the combination with mileage recording counters, impression devices coöperating with said counters in taking records therefrom of the mileage a car has traveled, and means controlling the operations of said impression devices, a valve controlling the passage of motive fluid to the engine of said car, and connections between said valve and the impression devices whereby the valve is opened in one operation of the impression devices and is closed in the next succeeding operation of said impression devices.

3. In a machine of the character specified, the combination with mileage recording counters, impression devices coöperating therewith in taking records from said counters of the mileage a car has traveled, of means controlling the discharge of motive fluid to the engine of said car, said means being actuated from the impression devices when said impression devices are operated.

4. In a machine of the character specified, the combination with mileage recording counters, impression devices coöperating therewith in taking records from said counters of the mileage a car has traveled within any given period, and a key controlling the operative relation of the impression devices and said counters, of a valve controlling the admission of motive fluid to the engine of said car, said valve being actuated from an operation of the impression devices after said impression devices have been unlocked by said key.

5. In a machine of the character specified, the combination with mileage recording counters, impression devices coöperating therewith in taking records from said counters of the mileage a car has traveled in any given period, and a key controlling the operative relation between said counters and said impression devices, said key having means thereon for identifying with said record the person having said key, of a valve controlling the admission of motive fluid to the engine of said car, and means actuated from said impression devices for operating said valve when records are taken from the counters.

6. In a machine of the character specified, the combination of a valve controlling the admission of motive fluid to an engine, and printing mechanism including counters for taking a record of the mileage a car propelled by said engine has traveled, connections between said printing mechanism and said valve, and means for operating said

printing mechanism to actuate the valve to open or close the same.

7. In a machine of the character specified, the combination of a valve controlling the admission of motive fluid to an engine, 70 printing mechanism adapted in its alternative operations to open or close said valve, an identifying key controlling the operations of said printing mechanism, and means for locking said key in position after it has 75 released the printing mechanism.

8. In a machine of the character specified, the combination with an engine driven vehicle, of a valve controlling the admission of motive fluid to the engine of said vehicle, 80 printing mechanism adapted in one of its operations to open said valve and thereby admit motive fluid to said engine, and in the other of its operations to close said valve, means for locking said printing mechanism against operation, an identifying printing member by means of which the person operating said printing mechanism is identified with the record made thereby, and means actuated by said printing mechanism 85 to lock the identifying printing member in a printing position.

9. In a machine of the character specified, the combination with the mileage recording counters, impression devices for taking records from said counters showing the distance traveled by a car equipped with said machine, an identifying member serving to lock and unlock said means for taking said records, of a valve controlling the admission 100 of motive fluid to the engine of said car, a rotating member actuated concurrently with the operations of the record-taking means, and means interposed between said rotating member and said valve whereby the valve is 105 alternately opened and closed and thereby controls the admission of the motive fluid to the engine.

10. In a machine of the character specified, the combination of a valve controlling 110 the admission of motive fluid to an engine, means for actuating said valve including a rotating member, printing members including a mileage counter adapted to record the miles traveled by a car driven by said engine, impression devices coöperating with said printing members in taking such records, means interposed between said impression devices and said rotating member 115 for driving said rotating member whereby 120 the valve is actuated alternately to admit the motive fluid to the engine.

11. In a machine of the character specified, the combination with a mileage printing counter, means for actuating said 125 counter from a rotating part of the vehicle, impression devices coöperating with said counter in taking records of the mileage traveled by said vehicle, a key controlling the operative relation between said impres- 130

- sion devices and said counter and adapted to furnish an impression identifying the person using said key with said record, a valve controlling the admission of the motive fluid to the engine of said vehicle, said valve being operated from the impression mechanism, and means for printing the dates upon said records to identify the mileage records therewith.
10. 12. In a machine of the type specified, the combination with a mileage printing counter, means for actuating said counter from a rotating element of a vehicle, date and serial numbering printing devices co-operating with the mileage printing counter in furnishing a record, impression mechanism co-operating with said printing counter and devices in taking such records, and valve controlling the admission of motive fluid to the engine of said vehicle, said valve being operated from the impression devices to exclude and admit the motive fluid to the engine.
15. 13. In a machine of the character specified, the combination with a valve controlling the admission of motive fluid to the engine of a power driven vehicle, of printing mechanism connected with said valve and serving to operate the valve to open or close the same on the alternate operations of said printing mechanism, and a key controlling the operative relation between the printing mechanism and the valve.
20. 14. In a machine of the character specified, the combination with a valve controlling the admission of motive fluid to the engine of said vehicle, of printing mechanism adapted in its alternate operations to open or close said valve, and means for locking and unlocking the printing mechanism, said means serving to identify the person operating said printing mechanism and said valve.
25. 15. In a device of the character specified, the combination with a mileage printing counter, and impression devices co-operating therewith in taking records from said counter showing the mileage a car equipped with said machine has traveled, of a valve controlling the admission of the motive fluid to the engine of said car, a cam actuated from the operations of the impression devices and reciprocal connections between the valve and the cam whereby the valve is alternately opened and closed on each alternate operation of the impression devices.
30. 16. The combination with a power driven vehicle, of means carried thereby for taking a record showing the mileage said vehicle travels for any given period of time and including the dates of each record and means for identifying the person taking such record, of impression devices for said record-taking means, a key controlling said impression devices, and a valve controlling the admission of motive fluid to the engine of said vehicle, said valve being operated from the impression devices.
- In testimony whereof we affix our signatures.
